(57) **CLAIM**

The ornamental design for an off-road vehicle as shown and described.

DESCRIPTION

FIG. 1 is a perspective view taken from a top, front, left side of an off-road vehicle according to our design;

FIG. 2 is a perspective view taken from a top, front, right side thereof;

FIG. 3 is a perspective view taken from a top, rear, right side thereof;

FIG. 4 is a perspective view taken from a top, rear, left side thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof; and,

FIG. 10 is a bottom plan view thereof.

Throughout the Figures, where shown, the dashed broken lines shown in the drawings are for the purpose of illustrating portions of the article and form no part of the claimed design.

1 Claim, 10 Drawing Sheets
